REFRIGERATION APPARATUS

William G. Mayer, Pittsburgh, Pa., assignor, by
mesne assignments, of one-half to Adico De-
velopment Corporation, New York, N. Y., a cor-
poration of New York, and one-half to Inter-
national Carbonic Engineering Company, Wil-
mington, Del., a corporation of Delaware

Application May 4, 1931, Serial No. 534,721

8 Claims. (Cl. 62—91.5)

This invention relates to the preservation of perishable materials, and more particularly to the refrigeration of vehicles by means of solid carbon dioxide.

5 Ordinary water ice as a refrigerant for vehicles, such as trucks, carrying foodstuffs is not satisfactory, for various reasons. Chief among these are the large bulk and weight of ice and brine which must be carried, and the rather limited 10 cooling effect and refrigeration period available. Also, the refrigerating effect is quite restricted.

The advantages of solid carbon dioxide, e. g., 15 in the form of so-called snow or ice, are well known. Its temperature is about —115° F., and it does not melt, but sublimes. It thus provides greater refrigerating possibilities than water ice, and it eliminates the collection of liquid with its attendant disadvantages. In general 1 pound of 20 solid carbon dioxide is capable of the same refrigerating effect as about 15 pounds of water ice. Thus lower temperatures, with better preservation of foodstuffs, are possible, and pay loads and route lengths may be increased. Furthermore, solid carbon dioxide does not require the brines needed 25 with water ice, so that this source of non-pay weight, and the corrosion due to brine, are eliminated.

These properties render solid carbon dioxide an 30 ideal refrigerant, particularly for vehicular transportation of perishables. However, it is substantially more expensive weight-for-weight than water ice; gaseous carbon dioxide formed on evaporation may exert an injurious effect on some 35 foods; and its use requires some measure of temperature control, since otherwise foods refrigerated with it may be frozen. Therefore, trucks and similar vehicles using carbon dioxide refrigerant must be adapted to prevent undue evaporation of the carbon dioxide and contact of the 40 gas with its load, as well as providing for temperature control. The constructions, whether vehicular or stationary, available heretofore have not achieved these ends satisfactorily.

45 It is among the objects of this invention to provide a refrigerating unit for use with solid carbon dioxide which is compact, sturdy, efficient, affords maximum refrigerating effect, in which the rate of heat transfer can be adjusted over a wide 50 range, which eliminates contact of CO₂ gas with the refrigerated materials, and utilizes the gas given off by evaporation of the solid carbon dioxide to aid in the refrigeration. Other objects and advantages will appear hereinafter.

55 The apparatus provided by the invention com-

prises a suitable refrigerator compartment in which there is disposed a container for solid carbon dioxide. Surfaces of the container are exposed to the compartment, and it is provided with means for increasing the normal rate of heat transfer between the compartment and the refrigerant, which most suitably takes the form of a base plate provided with fins. Means are provided also for controlling the rate of heat transfer, and thus the degree of refrigeration, which in the preferred embodiment includes means for increasing or decreasing the radiating area of the solid CO₂ relative to the compartment. The construction is such that leakage of substantial amounts of gaseous carbon dioxide into the compartment is prevented, this gas being preferably led into the insulated walls of the compartment to enhance the cooling effect. Also, the container is preferably adapted to retain the gas under a predetermined pressure. Through these means the refrigeration efficiency is increased.

Although the invention is not limited to its application to vehicles, it is particularly adapted for use therewith and will be so described. In the accompanying drawings, Fig. 1 is a fragmentary side elevation of a truck having a refrigerated body compartment embodying the invention, parts being broken away for clarity of illustration; Fig. 2 an enlarged perspective view of the carbon dioxide container shown in Fig. 1; Fig. 3 a perspective view of an insulating pad for use with the container of Figs. 1 and 2; Fig. 4 a cross sectional view of the compartment and unit shown in Figs. 1 and 2; Fig. 5 a plan view of the unit taken on line V—V, Fig. 4; and Fig. 6 a plan view of the cover of the unit.

Referring to Figs. 1 to 6 a truck chassis 1 is provided with a body 2 having double walls 2^a, filled with suitable heat insulating material 3, such as the fibrous insulators now commonly used, for instance kapok or balsa wool.

40 A container for solid carbon dioxide projects into the refrigerating compartment thus formed, preferably through its top, as shown in Figs. 1 and 4, and in order to provide good heat transfer between its container refrigerant and the compartment, the container is formed of a metal of high heat conductivity, preferably aluminum. Its side walls 4 are joined to a base to form a rectangular container whose cross sectional dimensions are such as to provide for the insertion of the standard solid blocks of carbon dioxide now in use, or multiples or uniform fractions thereof.

The container is preferably provided with means for increasing its normal heat radiating capacity, such as fins. Most suitably this is accomplished by the use of a base plate provided with fins. The preferred embodiment, as shown in the drawings, comprises a metallic base plate 5 connected to the side walls and projecting laterally therebeyond. Various types of heat conducting fins may be used, the embodiment shown comprising V-shaped fins formed by bending sheet metal to form corrugated strips 6. On the upper side of base 5 these are connected to the portions which extend beyond the container walls, and are welded to the latter. They also extend entirely across, and are connected to, the lower side of plate 5. This construction increases the heat conducting area, as compared with ordinary flat and straight fins, and it provides channels for circulation of air. Preferably base 5 and strips 6 are provided with holes 7, and slots 8 are cut in plate 5 and strips 6, to increase the circulation of air over the side walls. This construction, with metallic connection between the fins, side walls and base, further enhances the heat transfer.

In order to render the container proof against leakage of CO₂ gas into the compartment, the side walls and base are preferably welded together. The container projects into the compartment through a hatchway having side walls 9, Figs. 1 and 4, to which it is connected, and with which it makes a snug fit to prevent leakage of substantial amounts of gas into the compartment.

The construction thus provided is adapted to efficiently refrigerate the compartment, but because regulation of temperature is desirable, either to prevent freezing of the materials carried, or to keep them at a desired temperature, and also to reduce CO₂ consumption, means are provided for regulating the compartment temperature to a desired predetermined value, by regulating the rate of heat transfer between the compartment and the solid carbon dioxide.

In accordance with the invention temperature control is effected by vertical adjustment of the container, or of the CO₂ refrigerant, or both. As shown in Fig. 2, side plates 4 are provided with a plurality of horizontal rows of holes 10 for connecting the container to side walls 9 of the hatchway by means of screws. In this manner the container may be adjusted in the hatchway to vary the vertical exposure *x*, Fig. 4, of its side walls, thus increasing or decreasing the refrigerating effect as need be, both by altering the exposed heat conducting side wall area, and by varying the relative area of solid CO₂ exposed to the compartment through the container side walls. By the use of a plurality of rows of staggered holes 10 this adjustment is provided for, and leakage of gas between the container and hatchway walls is minimized.

Further control is afforded also by means of insulating pads placed under the blocks 11 of solid carbon dioxide. Such pads reduce the rate of heat transfer through the base plate by eliminating direct contact of the blocks 11 with plate 5. They also reduce the area of CO₂ exposed to the compartment through the side walls. A particularly suitable insulating pad is shown in Fig. 3. It comprises a hollow gas-tight box-like structure 12 formed of metal, and to increase its strength there is disposed within it a corrugated metallic reinforcing member 13. This adds strength while retaining the heat-insulat-

ing effect of the dead air space in the box. By the use of one or more of these mats the blocks of CO₂ may be raised vertically in the container, thus eliminating the necessity for adjusting the container vertically, or contributing further temperature control in conjunction with such adjustment.

I have found that evaporation of the solid CO₂ refrigerant may be retarded, and refrigerating efficiency increased, by retaining under pressure in the container the gaseous CO₂ which forms as the solid CO₂ evaporates in absorbing heat from the compartment. To this end the hatchway is closed by a heat-insulated cover 14 pressed against a gasket 15 by spring latches 16 which engage catches 17 on hatchway side walls 9.

The pressure may be relieved through an outwardly opening relief valve 18 disposed in one of the hatchway walls, this valve being adjustable to maintain the pressure at a desired predetermined value, for example 5 to 15 pounds. This CO₂ gas is quite cold, and while it may be relieved to the atmosphere, it is preferred to use it as an additional refrigerant. For this purpose valve 18 opens into the insulation space between side walls 2^a, and circulates through insulation 3 surrounding, thus cooling the compartment walls. In order to permit free circulation, the body structural members 19 are provided with holes 20 as need be. The gas finally escapes to the atmosphere through catches 17 on hatchway side walls 9.

The containers may be of any desired size, depending upon the size of the compartment, the length of haul, and the degree of refrigeration needed. They may be adapted to take a single, or a plurality of blocks, disposed horizontally, or stacked vertically.

Where the containers are to accommodate more than one block of carbon dioxide, it is preferable to secure partition plates 21 therein to form an individual compartment for each block, so that as the blocks evaporate they will stay more or less in place and not shift about.

In the use of the refrigerator unit thus provided the container is adjusted to provide an exposed vertical distance *x* such as to maintain the desired temperature in the compartment. This may be done when assembling the vehicle, the builder knowing from the size of the compartment and the container capacity what exposure to provide in order to obtain any desired temperature. It has been found that, in general, five pounds per square inch gas pressure in the container is sufficient to retard evaporation satisfactorily, and pressures up to 15 pounds do not result in any appreciably greater retardation. In order to prevent extreme pressure within the chamber, should the valve fail to function, latches 16 are resilient enough to allow the gas to escape past gasket 15 after it has reached a pressure of a few pounds above that for which the valve is set.

Solid carbon dioxide blocks are placed in the container, the cover is set in place, and the latches sprung under the catches, thereby tightly sealing the chamber. As evaporation of the CO₂ proceeds to a point where the gas pressure within the chamber exceeds the pressure valve 18 is set for, the excess pressure is relieved through the valve and the gas circulates through insulation 3 about all parts of the walls, and still further aids in cooling the compartment.

In case insulation 3 is not a fibrous or loose material, but is cork or the like, valve 18 may open into the outside atmosphere. Where meat

and the like, which are improved by carbon dioxide gas, are carried the valve may open into the compartment to allow the gas to come into direct contact with such materials.

5 If it is desired to raise the temperature in the compartment higher than that initially provided for, the container may be raised by removing the screws from holes 10 and elevating it, or one or more pads of the type described may be placed 10 under the block to separate it from direct contact with the base radiation plate. By having a number of such pads of various thicknesses to select from, a wide range of temperature control will be made possible. Actual tests have shown that by 15 varying the vertical position of the container and by using insulating pads, a temperature range of between 40° F. below zero to 15° F. above can be obtained.

For large vehicles, and for special purposes, 20 any desired number of the units may be used, and they may be disposed otherwise than through the roof, where this appears to be desirable. The construction described is preferred, however, because the interior of the units are readily accessible through the roof, the units do not interfere materially with the insertion and removal of goods in the compartment when the units are in this position, and because warm air tends to rise to 25 the roof.

30 The unit provided by this invention requires but a small amount of space in a refrigeration compartment, as compared with water ice units, which results in providing more space for food, and larger pay loads. Furthermore, as the unit is 35 relatively small, and is preferably constructed of a light metal, such as aluminum, lighter trucks can be used, which decreases the initial vehicle cost, and its upkeep, and also increases the area 40 of the district that can be served by a single vehicle. As the container and radiation plate extend such a short distance into the refrigeration compartment, they interfere but little with efficient packing of the latter with foodstuffs. By 45 having the gas pass into the insulation the carbon dioxide is made to serve twice, first by means of the radiation plate, and second by keeping the walls cold.

According to the provisions of the patent statutes, I have explained the principle and mode of 50 operation of my invention and have illustrated and described what I now consider to represent its best embodiment. However, I desire to have it understood that, within the scope of the appended claims, the invention may be practiced 55 otherwise than as specifically illustrated and described.

I claim:

1. An apparatus for preservation of perishable 60 materials comprising the combination of a refrigerating compartment for said materials, a container for solid carbon dioxide refrigerant projecting downwardly through the compartment roof and having a base and side walls of metal of high thermal conductivity connected to 65 prevent leakage of substantial amounts of gaseous carbon dioxide into the compartment, means for maintaining gaseous carbon dioxide in the container under a predetermined pressure, 70 said base having metallic heat conducting means connected thereto and extending laterally of the container walls, and means for adjusting said solid carbon dioxide vertically of the compartment to control the temperature of said materials by regulating the rate of heat transfer between 75 the compartment and refrigerant.

2. An apparatus for preservation of perishable materials comprising the combination of a refrigerating compartment for said materials provided with a hatchway through the roof, a container for solid carbon dioxide refrigerant projecting into said compartment through and vertically adjustable in said hatchway, said container having side walls and a base plate formed of metal of high heat conductivity and having its side walls cooperating with the hatchway to prevent leakage of substantial amounts of gaseous carbon dioxide into the compartment, said base plate extending outwardly beyond said side walls and being provided with corrugated metal plates forming open channel V-shaped heat-conducting fins, and a removable closure for said hatchway. 10 15

3. An apparatus for preservation of perishable materials comprising the combination of a refrigerating compartment for said materials provided with a hatchway through the roof, a container for solid carbon dioxide refrigerant projecting into said compartment through and vertically adjustable in said hatchway, said container having side walls and a base plate formed of metal of high heat conductivity and having its side walls cooperating with the hatchway to prevent leakage of substantial amounts of gaseous carbon dioxide into the compartment, said base plate extending laterally beyond said side walls and being provided with corrugated metal plates forming open channel V-shaped heat-conducting fins, a removable closure for said hatchway, said container retaining gaseous carbon dioxide gas under pressure in the container, and a relief valve associated with said container for maintaining said gas under a predetermined pressure. 20 25 30 35

4. An apparatus for preservation of perishable materials comprising the combination of a refrigerating compartment for said materials bounded by double heat insulated walls and provided with a hatchway through the roof, a container for solid carbon dioxide refrigerant projecting into said compartment through and vertically adjustable in said hatchway, said container having side walls and a base plate formed of metal of high heat conductivity and having its side walls cooperating with the hatchway to prevent leakage of substantial amounts of gaseous carbon dioxide into the compartment, said base plate extending laterally beyond said side walls and being provided with corrugated metal plates forming open channel V-shaped heat-conducting fins, a removable closure for said hatchway, said container retaining gaseous carbon dioxide under pressure in the container, a relief valve connecting said container with the space between said double walls, means for varying the relative area of solid carbon dioxide exposed to the compartment through the walls to further regulate the temperature within said compartment, and means for increasing air circulation over said heat-conducting fins. 40 45 50 55 60

5. A refrigerator for transportation of perishable materials comprising in combination a vehicle having a refrigerating compartment enclosed by double walls having a space therebetween filled with a heat insulator, said compartment being provided with a hatchway through the roof, a container for solid carbon dioxide refrigerant 70 projecting into said compartment through and vertically adjustable in said hatchway, said container having side walls and a base plate formed of metal of high heat conductivity and having its side walls cooperating with the hatchway to 75

prevent leakage of substantial amounts of gaseous carbon dioxide into the compartment, said base plate extending laterally beyond said side walls and being provided with corrugated metal plates 5 forming open channel V-shaped heat-conducting fins, a removable closure for said hatchway, said container retaining gaseous carbon dioxide under pressure, and a relief valve associated with said container whereby to maintain said pressure at 10 a predetermined point and adapted to permit the gas in excess of the pressure desired to escape into said double walls in order to further cool the compartment, means for insulating the solid carbon dioxide from the container in order to 15 further regulate the temperature within said refrigerating compartment, and means for increasing air circulation over said heat-conducting fins.

6. An apparatus for preservation of perishable materials comprising the combination of a refrigerating compartment for said materials, a container for solid carbon dioxide refrigerant projecting downwardly into said compartment from its roof, said container having side walls and a base plate formed of metal of high heat 20 conductivity associated to prevent leakage of substantial amounts of gaseous carbon dioxide into the compartment, said base plate being provided on the side exposed to said compartment with means providing increased heat exchanging 25 surface, and one wall of the container being provided with a removable gas-tight closure for introduction of solid carbon dioxide into the container and for retention of carbon dioxide gas therein, and means for adjusting said solid carbon dioxide vertically of the compartment to 30 control the temperature of said materials by regulating the rate of heat transfer between said compartment and refrigerant.

7. An apparatus for preservation of perishable materials comprising the combination of a refrigerating compartment for said materials, a con- 40

tainer for solid carbon dioxide refrigerant associated with the roof of said compartment and projecting downwardly therein, the container having a base and side walls of metal of high thermal conductivity associated to prevent leakage of substantial amounts of gaseous carbon dioxide into the compartment, a removable gas-tight closure for the container for introduction of solid carbon dioxide into the container and for maintaining gaseous carbon dioxide therein under pressure, the base of said container having on the side exposed to said compartment increased heat exchanging area, a relief valve associated with the container for maintaining said gas under a predetermined pressure therein, and means for adjusting said solid carbon dioxide vertically of the compartment to control the temperature of said materials by regulating the rate of heat transfer between the compartment and refrigerant.

8. An apparatus for preservation of perishable materials comprising the combination of a refrigerating compartment for said materials, a container for solid carbon dioxide refrigerant projecting downwardly through the compartment roof and adjustable vertically of the compartment, the container having a base and side walls of metal of high thermal conductivity connected to prevent leakage of substantial amounts of gaseous carbon dioxide into the compartment, means for maintaining gaseous carbon dioxide in the container under a predetermined pressure, said base having on the surface exposed to said compartment increased heat exchanging surface, and means for adjusting said solid carbon dioxide vertically of the compartment to control the temperature of said materials by regulating the rate of heat transfer between the compartment and refrigerant.
